UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,089,553.

Specification of Letters Patent. Patented Mar. 10, 1914.

Application filed June 11, 1910. Serial No. 566,383.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had thereto in the accompanying drawings.

10 The invention relates to car roof construction, and it is the particular object of the invention to obtain a construction in which the space occupied by the roof structure is reduced to the minimum thereby increasing the capacity of the car.

15 It is the further object to obtain a strong light durable construction, and one which is thoroughly weather proof.

20 With these objects in view the invention consists in the construction as hereinafter set forth.

In the drawings,—Figure 1 is a cross section of a car to which my roof is applied. Fig. 2 is a vertical longitudinal section on line $x-x$. Fig. 3 is a similar view showing a modified construction. Fig. 4 is an elevation showing the manner of splicing the purlins.

25 My improved roof belongs to that type in which the roof spans are formed solely by metal sheets, said sheets being supported on a frame composed of carlines and purlins. It is usual in the construction of the frame to arrange the carlines and the purlins in 30 different planes, the one overlapping the other, but this necessitates a clearance equal to the combined thickness or depth of both members. I have reduced the thickness of the roof arranging both carlines and purlins 35 within the vertical dimensions of the one, the construction being as follows: A are the carlines preferably formed of channel bars or other structural shape of beam, B are purlins formed of wood. The depth of 40 thickness of these purlins is greater than that of the carlines, and the upper faces of both carlines and purlins are arranged on the same plane so as to form a support for the roofing sheets.

45 To permit arrangement as above described the purlins are formed in sections comprising a lower section C extending uninterruptedly the entire length of the car, and upper sections D which are arranged above the section C, and have their ends abutting

against adjacent carlines A. To increase the rigidity filler blocks E are placed within the channels of the carlines opposite the ends of the sections D so that longitudinal stresses will be transmitted from one section to another. The sections C and D are united in any suitable way as by wood screws F, the carlines and purlins are also secured to each other by bolts G passing through the center of the intersection.

45 The roofing sheets H are provided with upstanding marginal flanges I, at their opposite edges which are covered by a cap J preferably of U shape cross section. Clearance is provided for the flanges I to permit the sheets H independent movement, thereby avoiding rupturing the sheets by distortion of the roof frame. I have also provided a spacer between the flanges I of adjacent sheets, this being preferably a wooden 50 strip I' extending from eaves to the ridge of the car. This spacer is secured to the carlines and purlins by the bolt G which passes therethrough and serves the further function of reinforcement of compression 55 member of the carlines.

55 In the construction illustrated in Fig. 2 the carline A is in the form of a channel beam having its flanges at opposite sides and extending downward. In Fig. 3 a modified construction is shown in which the beam is provided with the laterally extending flanges K beyond the downwardly extending flanges L said lateral flange forming the support for the roofing sheets. With 60 both constructions the purlins are formed of a continuous lower section and a series of upper sections which abut against the carlines and have their upper faces flush with the upper face of the carlines.

65 To make the reinforcement of the carline by the spacer strip I' effective, I preferably provide a ridge cap M with depending lugs or flanges N which form abutments for the end of the spacer. This will cause the compression stresses developed in the strip I' to be transmitted from eave to eave, thereby 70 strengthening the metallic carline.

75 The purlin may if desired, be formed of either sections spliced to each other. That is, in place of using a lower section C which extends the entire length of the car, this section may be abutted against a similar section at a point intermediate the carlines. As 80 shown, in Fig. 4, the sections C' and C' abut 85

against each other and are secured by the section D which extends between adjacent carlines. The overlapping of these sections will thus form a splice which will make the 5 purlins as effective as if composed of a single bar.

What I claim as my invention is:

1. In a car roof, the combination with carlines, of a purlin of greater depth having its 10 upper face flush with the upper faces of the carlines and having a lower portion extending uninterruptedly beneath said carlines, and roofing sheets supported on the flush faces of said carlines and purlins.
- 15 2. In a car roof, the combination of metallic carlines and wooden purlins arranged with their upper faces on the same plane, roofing sheets supported on said carlines, and purlins having upturned flanges and caps 20 above said carlines covering said flanges.
- 25 3. In a car roof, the combination with metallic carlines, of wooden purlins having their upper faces flush with the upper faces of said carlines, roofing sheets supported on said carlines and purlins, and wooden strips extending longitudinally on said carlines forming spacers for said sheets and reinforcements for said carlines.
- 30 4. In a car roof, the combination with metallic carlines, of wooden purlins having

their upper faces flush with the upper faces of said carlines, roof sheets supported on said carlines and purlins, and wooden strips extending longitudinally of each carline forming a spacer for said sheets and a reinforcement for said carline, and a ridge cap having abutment thereon for said spacer. 35

5. In a car roof, the combination with metallic carlines formed of channel bars, of purlins arranged with their upper faces in 40 the same plane, roofing sheets supported on the flush faces of said carlines and purlins, wooden strips extending longitudinally on said carlines forming spacers for said sheets and reinforcements for said carlines, and 45 filler blocks within the channels of the carlines.

6. In a car roof, the combination with metallic carlines formed of channel bars, of purlins arranged with their upper faces in 50 the same plane, and wooden strips extending longitudinally below said carlines and within the channels thereof for transmitting the stress of one section of the purlin to another. 55

In testimony whereof I affix my signature in presence of two witnesses.

DAVID W. HAWKSWORTH.
